UNITED STATES PATENT OFFICE.

MAXWELL R. KARGE, OF PHOENIX, NEW YORK, ASSIGNOR TO THOMAS P. KINGSFORD,
OF OSWEGO, NEW YORK.

AUTOMATIC REFRIGERATING APPARATUS.

Application filed May 14, 1923. Serial No. 638,854.

To all whom it may concern:

Be it known that I, MAXWELL R. KARGE, a citizen of the United States of America, and a resident of Phoenix, county of Oswego, and State of New York, have invented certain Improvements in and Relating to Automatic Refrigerating Apparatus, of which the following is a specification.

This invention relates to refrigeration apparatus of the absorption type; and the objects and nature of the invention will be readily understood by those skilled in the art in the light of the following explanations of the accompanying drawings illustrating what I now believe to be the preferred mechanical expression or embodiment of my invention from among other forms, constructions and arrangements within the spirit and scope thereof.

An object of the invention is to provide simple and efficient refrigerating apparatus of the absorption type that will be automatic in operation and that will overcome certain of the complications involved in absorption refrigeration machines heretofore proposed.

With this, and other, objects in view my invention consists in certain novel features in construction, and in combinations and arrangements as more fully hereinafter described and specified.

Referring to the accompanying drawings, forming a part hereof:

Fig. 1 is a more or less diagrammatical elevation of a refrigerating machine embodying my invention, the refrigerating members thereof being shown in a refrigerator, partially broken away and illustrated in sectional elevation.

Fig. 2 is a sectional elevation of the refrigerating machine, parts being broken away and the refrigerating members not being shown.

Fig. 3 is an edge elevation of the machine, parts being broken away and the refrigerating members not being shown.

Fig. 4 is an electric wiring diagram of the machine of Fig. 1, parts being diagrammatically illustrated, a plug being shown for insertion into a socket in a building electric wiring system as the source of electric power.

Fig. 5 is a detail elevation of the valve controlling the flow of cooling water and the switch mechanism controlling the electric

heaters, the valve being shown at its limit of downward movement.

Fig. 6 shows the constructions of Fig. 5 in longitudinal or vertical section, the valve being shown at its limit of upward movement.

Fig. 7 shows one of the refrigerating members in horizontal section.

Fig. 8 shows the refrigerating members in top plan, modified supporting and connecting means being shown.

Fig. 9 shows the refrigerating members of Fig. 8 in front elevation, the front doors being removed.

Fig. 10 shows the structure of Fig. 8 in front elevation showing the doors in normal closed position.

Figs. 11 and 12 show a form of ice forming pan or tray in top plan and end elevation.

The machine of my invention embodies two preferably similar generator-absorbers A, B, of like capacity, each charged with a suitable absorbent and a suitable refrigerant, the two generator-absorbers preferably containing similar charges of like materials. For instance, aqua-ammonia, although other refrigerant gases and absorbents can be employed, as will be appreciated by those skilled in the art.

Each generator-absorber embodies a strong rigid retort or tank 1 permanently sealed and closed except as hereinafter appears and capable of withstanding the maximum internal pressure to which it might be subjected even under abnormal conditions. Each tank is jacketed to receive a cooling medium to absorb or conduct off the heat of absorption. For instance, for this purpose, I show water jacket or tank 2 providing a water space below as well as around and above, the retort 1, although I do not wish to so limit my invention.

Each generator-absorber is provided with its individual independent gas line condenser, and refrigerating element or expansion chamber, but the two separate refrigerating elements cooperate in lowering the temperature of the zone, space, chamber or material to be refrigerated, in that both said elements are located in such zone or the like, preferably in juxtaposition or in close proximity to each other.

In the embodiment illustrated, the two

generator-absorbers are not connected in parallel with an expansion or refrigerating chamber in one gas line circuit that includes a liquid ammonia receiver, but each generator-absorber has its own gas line to a refrigerating element, and this line, in part, forms the pressure line as well as the suction line, and, in this example, avoids the use of a liquid refrigerant receiver, an expansion valve and certain other complications.

For instance, in the example illustrated, I show two separate similar refrigerating elements A', B', arranged in the zone to be refrigerated. I show these elements arranged in parallelism one over the other in close proximity, although I do not wish to so limit my invention. In this instance, each refrigerating element consists of an air and liquid tight strong walled hollow metal body to form a refrigerant receiver and expansion or "boiling" chamber of relatively large capacity, that is approximately U-shaped in form and horizontally arranged and preferably circular in cross section.

Each such element has its own liquid intake and expanded gas outlet pipe (5 or 5') opening thereto through the top wall thereof and this pipe is included in a pipe line that includes a condenser and that ultimately branches to provide a hot gas offtake from the top of the interior of its generator-absorber and an expanded gas or suction intake opening into the lower part of such generator absorber, preferably below the liquid level therein.

Referring in this connection to the particular construction illustrated for purposes of explanation, hot gas offtake pipe 3 opens through the top of generator-absorber A and extends therefrom to condenser 4 while pipe 5 leads from the condenser to and opens into the top of the refrigerating element A' of the said generator-absorber A, and thus completes the supply pipe line from generator-absorber to refrigerating element. The expanded gas or suction line from the refrigerating element back to the generator-absorber, is formed by said supply pipe line and is completed by the provision of a branch pipe 7 leaving pipe 3, at a point between the condenser 4 and a check valve 6 in line 3, and extending through the top of generator-absorber A to a point near the bottom thereof where it discharges the expanded gas into the liquid in the generator absorber. This suction branch 7 is equipped with a check valve 8 to close the branch against back pressure flow from the generator-absorber. The check valve 6 in the gas offtake pipe 3 is constructed and arranged to prevent back pressure flow toward the generator and to perform certain other functions as will be pointed out hereinafter.

The generator B is likewise independently

connected with its own refrigerating element B', through a separate line including a pipe 3', check valve 6', condenser 4' and pipe 5', and the suction connection is likewise completed through branch 7' having check valve 8', all operating and arranged as described in connection with generator A and its refrigerating element A'.

Those skilled in the art know that under heat and pressure, the gas such as anhydrous ammonia, is gradually driven from the liquid in the generator-absorber and flows into the condenser and is therein reduced to liquid form. In the machine of my invention, this liquid refrigerant gradually flows directly from the condenser into the expansion chamber (the refrigerating element) wherein it accumulates during the generating stage so that this element then acts as a receiver. When the liquid or other absorbent in the generator has been approximately exhausted of gas, and the "critical point" has been reached as determined by temperature and pressure in the generator, the application of heat to the generator is stopped and the generator is thereupon cooled in any suitable manner or by any suitable means. By cutting off the heat and application of cooling medium, generation gradually ceases, and the temperature and pressure within the generator gradually drop and minus pressure gradually develops and the absorption stage thereupon starts in. When the pressure within the generator-absorber becomes minus, i. e., less than that in the refrigerating element, the anhydrous ammonia or other refrigerant in the refrigerating element begins to "boil" or gradually expand into gas and the absorption or refrigerating stage has started in. During this stage, the expanded gas is drawn from the refrigerating element back through pipe (5 or 5'), condenser (4 or 4'), pipe (3 or 3') to branch (7 or 7') into the absorbent in the particular generator-absorber wherein the gas is absorbed preparatory to repeating the generating stage hereinbefore described.

The check valve (6 or 6') is constructed and arranged to prevent gas flow through pipe (3 or 3') toward the generator-absorber, and the check valve (8 or 8') is constructed and arranged to prevent gas flow through pipe (7 or 7') from the generator-absorber, and hence when plus pressure exists in the generator-absorber, the flow therefrom can be only by way of pipe (3 or 3') and when minus pressure exists in the generator absorber, the flow thereto can be only by way of the pipe (7 or 7').

The check valve (6 or 6') in the pressure gas offtake pipe is constructed and arranged to control and regulate the off flow of hot gas and to perform the functions of a dehydrator, and also of an expansion valve,

and thereby avoid the complications, as well as certain disadvantages, incidental to the use of such added features.

The check valve (8 or 8') in the suction or expanded gas intake pipe is also constructed and arranged to regulate the flow of gas from the refrigerating element and prevent too rapid expansion and flow of gas into the generator and prevent a return flow of gas faster than it can be absorbed, with a consequent creation of back pressure and loss in refrigerating efficiency.

The several check valves shown in this example, are similar in construction, and each consists of a casing 9 included in and as a section of its pipe line, said casing providing a longitudinal vertical bore in continuation of the pipe line bore. The casing bore increases in diameter from its lower inlet end toward its upper outlet end to provide for gas expansion and to permit the formation of several aligned annular ball valve seats vertically spaced apart, with the upper seat of greater diameter than the lower seat. On the lower seat is arranged a relatively small or light weight spherical gravity ball valve 10 that is freely movable and capable of being lifted by pressure from below.

On the upper—large diameter—valve seat is arranged a relatively large and heavy spherical gravity ball valve 11, that is also freely movable vertically and capable of being lifted by the necessary pressure from below.

The balls 10, 11, are spaced apart to provide an intervening expansion chamber 12 in which the gas, admitted by elevation of the small ball 10, expands and wherein the pressure accumulates until sufficient to elevate the large ball 11 and permit upward passage of the gas.

The balls are usually composed of metal and the upper ball is usually about twice the diameter of the lower ball and hence relatively heavy in weight. These balls and their seats are designed to tightly seal the gas passage against back pressure flow. The balls elevate in succession, to permit gas flow by stages, so that one ball seals the passage when the other ball lifts to permit flow.

When in action, the balls usually vibrate up and down or pulsate, and are constructed, arranged, and proportioned to suit the requirements of each installation, to approximately maintain more or less even pressure in the generator-absorber when generating to prevent sudden and wide pressure variations, and to control the flow back to the generator during absorption to prevent generation of back pressure and to prolong the refrigerating period.

In the offtake check valves (6 or 6') the hot gas passing up through the small lower valve seat, expands in the chamber below

the large ball 11 and is halted by the large ball, and hence such check valves serve the purpose of separators or dehydrators, as watery vapors are thereby separated from the gas and condensed in said expansion chambers. The water of condensation, gradually seeps down past the small valves 10 as they elevate and returns to the generator-absorbers.

In the particular example illustrated, the two condensers 4, 4', are formed by jackets on lengths of a coiled cooling water pipe. For instance, I show a vertically arranged cooling water pipe coil embodying a plurality of parallel horizontal pipe lengths 14, 80 arranged in a vertical series and connected so that cooling water flows through all of said lengths, preferably upwardly through the coil from the water supply pipe 15 to the water offtake pipe 16.

These pipe lengths 14 are surrounded by separate longitudinal jackets 17 at their ends welded or otherwise secured to the pipe lengths to form liquid and gas tight annular gas spaces around the pipe lengths and extending longitudinally thereof for flow of gas in contact with the cool exterior surfaces of the pipe lengths. Several of these annular jacket gas spaces can be coupled together to form one of the condensers 4 or 4', 95 and the remaining coupled together to form the other condenser.

For instance, I show the hot gas offtake pipe 3 discharging into the annular gas space within the top jacket 17, said top jacket space being connected with the next jacket space below by vertical cross gas connection 17', (to form condenser 4) with the condensed gas offtake pipe 5 leading from the bottom of the last named jacket space to convey the condensed gas to cooling or refrigerating A'. In this instance, the condenser 4', is of similar construction and is formed by the two lower jacket formed gas spaces on lengths of the water pipe, corresponding ends of said spaces being connected by vertical cross connection 17', with the hot gas pipe 3' discharging into the upper side of the other end of the upper space and condensed gas pipe 5' leading from the under side of the corresponding end of the lower jacket space and discharging into the cooling element B'.

A most simple and efficient condenser construction is thus provided, and yet one that permits back flow therethrough of expanded gases under suction, all without the necessity of employing separate liquid receivers and expansion valves or manual controls in the gas line. However, I do not wish to limit all features of my invention, to the particular condenser construction and arrangements described.

As hereinafter more fully described, 130 means and arrangements are provided to

control the heating and cooling of the generator-absorbers so that during normal operation of the machine, one or the other of the generator-absorbers is being heated while 5 the other is being cooled with provision for automatically switching the heat from and the cooling water to one generator at the approximate termination of each generating stage and simultaneously turning the heat 10 on and stopping the flow of water to the other generator-absorber to approximately terminate each absorption stage.

The arrangement is such that during 15 normal operation, condensed refrigerant is being delivered to one or the other of the refrigerating elements while the gas is expanding in the remaining element and exerting its refrigerating action on the zone to be cooled, and the first named refrigerating 20 element which is not then acting to refrigerate, is subjected to the refrigerating action of the other element and the condensed gas therein is cooled thereby while awaiting its turn to act as a refrigerant.

25 Also, during normal action of the machine, hot gas is flowing forward through one condenser 4 or 4', while expanded gas is flowing back through the other condenser, yet the gases in both condensers are subjected 30 to the cooling water flowing constantly through both condensers.

It will be observed that should an abnormal pressure develop in the pipe line of either generator-absorber, a pressure greater 35 than that in the generator-absorber, so as to prevent passage of fluid through check valve 6 or 6', the pressure in the system can become equalized to restore normal conditions, by fluid flow through check valve 8 40 or 8' into generator-absorber A or B.

In the particular example illustrated, pipe 15 constitutes the source of water supply for the two condensers and the two generator-absorbers.

45 The condensers are included in the water circuit in series, and the generator-absorbers in parallel, in that the water flows through the condensers in succession and therefrom through one or the other of the 50 generator-absorbers and therefrom to waste. The water discharge pipe 16 from the condensers leads down to a suitable valve that directs the water flow through branch water pipe a , into the jacket of generator-absorber A, or else through branch water pipe b , into the jacket of generator-absorber B, while opening the drain pipe b' of generator-absorber B, and closing the drain pipe a' of generator-absorber A, or vice versa if 55 the water is flowing into generator-absorber B jacket and is cut off from generator-absorber A jacket. The two generator-absorber jacket drain pipes a' , b' , can, if so desired, discharge to drain or waste pipe 20. The water jackets of the two generator-

absorbers overflow at their upper ends through pipes 22, to drain or waste pipe 21, so that during absorption, the cooling water continuously flows up from branch pipe a , or b , that enter the lower ends of 70 the jackets through the jacket of generator-absorber A, or B, and out through top pipe 22 to drain 21 to maintain a constant upward circulation throughout the length of the generator-absorber, to carry off the heat 75 of absorption, while the water has been drained from the jacket of the other generator-absorber that is being heated, through the bottom drain pipe a' or b' . However, I do not wish to so limit all 80 features of my invention.

Various valve or other devices can be employed to shift the cooling water supply from one generator-absorber to the other and simultaneously start the operation of 85 draining the jacket of the generator-absorber from which the cooling water has been cut off, at each shift of the machine to reverse the operations in the generator-absorbers.

90 However, I have devised exceedingly simple and efficient valve means for controlling the cooling water supplied to the generator-absorbers. For instance, I show a suitably supported fixed tubular valve 95 casing 23 arranged between the lower ends of the two generator-absorbers, and formed with a longitudinal bore opening through the upper end thereof, with the waste pipe 20 opening into and extending down from 100 the lower end of this bore. Within the bore of this casing, I arrange a longitudinal elongated slide valve or plug 24 with a running fit. This plug or valve projects upwardly beyond the casing, usually through a packed joint or gland to prevent water leakage from the bore around the valve, although I do not wish to so limit my invention. The valve or plug is hollow and forms 105 a longitudinal water supply distributing bore or passage 25 and a lower longitudinal water discharge or drainage passage 26 to drain pipe 20. The upper end of passage 26 is closed from communication with the lower end of passage 25 by an imperforate partition spanning the interior of the 110 valve or plug.

115 The inlet ends of the branch water supply pipes a , b , are fitted in the casing 23 from opposite sides thereof so that their inlets 120 form radial outlet ports from the casing bore, and the plug or valve is formed with radial outlet ports 25^a, 25^b, from its water supply passage 25, that are arranged to register with the inlet ends of the pipes a , b , respectively. The outlet ports 25^a, 25^b, are arranged at different elevations so that the inlet to one pipe will be always closed by the wall of the plug or valve and against 125 flow of water when the inlet of the other 130

pipe registers with a port 25^a or 25^b and is receiving water. The arrangement is such that when the valve is at its limit of upward movement one pipe (such as pipe *a*, through 5 port 25^a) will be receiving cooling water while the other pipe (pipe *b*) will be cut off from the water supply, and when the valve is at its limit of downward movement the first named pipe (pipe *a*) will be cut off 10 from the water supply while the other pipe (pipe *b* through port 25^b) will be receiving water from the valve.

The two drain pipes *a'*, *b'*, likewise have 15 their inlets opening in opposite directions in to the lower end portion of the valve casing, and controlled by radial ports 26^a, 26^b, in the valve to the valve drain passage 26, and arranged at different elevations so that when the valve is at its limit of downward movement 20 one drain pipe (such as *b'*) will be closed and the other drain pipe (such as pipe *a'* through port 26^a) will be open, with the arrangement reversed when the valve is at its limit of upward movement. It will 25 thus be observed that the drain from the generator-absorber receiving cooling water is always closed, while the drain from the generator-absorber cut off from cooling water is always open, and this relative arrangement is maintained when the valve is 30 shifted.

The lower end of the cooling water pipe 16 leading from the condensers, is suitably coupled to the upper end of the valve in open communication with the water passage 25 so that said valve forms a distributor for said pipe and the cooling water. If so desired, the pipe 16 can be provided with a 40 flexible section, such as 16', to accommodate the short limited operative vertical reciprocation of the valve.

If desirable, a stop 25', can be provided to limit the upward movement of the valve, and spring means, such as 25'', can be provided, acting on the valve to return the same to its limit of downward movement.

As will be appreciated by those skilled in the art, gas generating heat can be applied to the generator-absorbers, by various means 50 and in various ways, and through various mediums, as by steam, gas or other flame, electricity or by other heat generating mediums.

The application of heat is cut off from the 55 generator-absorber being cooled, and heat is applied to the generator-absorber from which the cooling medium is cut off, and the cycle is shifted from one to the other as each absorbing stage or as each generating 60 stage is approximately completed.

Various means can be provided for automatically and simultaneously operating the valve 24 to shift the cooling water flow, and devices for shifting the heat from one 65 generator to the other. The shifting means

can be actuated or controlled automatically by time controlled means independent of temperature and pressure conditions within the generator-absorbers, or by means controlled by floats in the generator-absorbers, 70 or by means controlled by pressure or by temperature conditions within the system, all acting to control any suitable motor or power for performing the actual work of shifting valves, switches, or other devices 75 for throwing the heating means on and off, and controlling the water flow.

For instance, in the drawings, I happen to show electric resistance heaters for the 80 generator absorbers, with a switch device arranged to break the power circuit through the heater of one generator-absorber when the circuit is closed through the heater of the other generator-absorber, acting in connection with and in fixed relation to the cooling water controlling valve and a motor for throwing the switches and valve.

In this example I show any suitable motor 85 27 suitably supported in a fixed position above the cooling water supply valve 24, 90 and having operative connection 28 with said valve for elevating the same and controlling the vertical position thereof. The switch mechanism controlling the generator-absorber heaters is, in this instance, carried 95 and actuated by the cooling water valve mechanism. For instance, I show movable switch contact 29 carried by and depending and insulated from a bracket 29' fixed to and projecting laterally from the upper end 100 of the valve 24 and movable vertically therewith. This switch is electrically connected with one side of the electric power circuit and is arranged to electrically engage either one of two fixed switch contacts 30', 31'. 105 and to snap from one to the other as the valve rises and falls to close the power circuit through one and break the circuit through the other. The contact 30' is electrically connected through the electric heater 110 30 of the generator A to the other side of the power circuit, and the contact 31' is electrically connected through the electric heater 31 of the generator B to the other side of the power circuit.

The exposed contacts 30', 31', are spaced 115 apart and arranged in a vertical row and in this instance are insulated from each other and carried by an insulating base 32 fixed to the exterior of the valve casing 23.

The arrangement is such that when the valve 24 is at its limit of movement in one direction with the cooling water flowing through one generator-absorber jacket, the electric heater circuit for that generator-absorber will be broken and the heater out of action, while the electric heater circuit of the other generator will be closed and that heater in action. On the completion of an absorption generation stage, the valve 24

will be moved by the motor to its opposite limit of movement to switch the cooling water from one generator-absorber jacket to the other and the switch member 29 will 5 simultaneously snap from one fixed contact to the other to break one heater circuit and close the other and thus switch off the heater of one generator-absorber and throw the heater of the other into heating action.

10 Where gas burners are employed to heat the generators, the movement of valve 24 can also be utilized to throw gas valve mechanism to automatically switch the gas supply from one burner to the other simultaneously with the cooling water switching action.

Where electrical heaters for the generators are employed, I prefer to provide the generators with heater element receiving pockets 20 33 projecting into the liquid spaces of the retorts and open at their outer ends at the exteriors of the generator water jackets to removably receive the electric heater or resistance units 30, 31. Each pocket can be 25 composed of an imperforate metal tube tightly sealed at one end and open at the other end. These tubes project into the generator retorts and are tightly sealed in the walls thereof as by welding, with their 30 open ends projecting through the water jacket. Each tube or pocket 33 is preferably formed to removably receive one electric hot point or other heating element, so that said elements can be removed for replacement or repair. I prefer to provide 35 each generator with several pockets 33 and electric heater units so that added heater units can be coupled into the heating circuits during very hot weather or in hot 40 climates to shorten the generating and absorbing stages and hence increase the refrigerating action. The number of heating units in the generators can thus be increased or decreased, as refrigerating conditions require.

As hereinbefore stated, various means can be employed to cause the motor, at the required intervals of time, to operate the valve 24 to switch the cooling water from 50 one generator to the other and simultaneously cut the heat from the last named generator and apply heat to the first named generator. In the particular example illustrated, I show each generator provided with 55 a thermostat for actuating a switch controlling an independent circuit for starting an operative valve throwing stroke or action of the motor 27. I also show each generator or its pipe line equipped with a pressure 60 gage for actuating another switch controlling another independent circuit for starting an operative valve throwing stroke or action of the motor 27, whatever the type or character of that motor.

65 For instance, each generator-absorber A,

B, is equipped with its own thermostat 35 preferably projecting into the retort thereof provided with and controlling its own electric switch 36 that makes and breaks its own electric circuit that includes the motor 70 27 or that includes means to cause said motor to perform an operative valve throwing stroke and then come to rest. Either one of the two thermostat controlled switches 36, can thus cause the motor 27 to perform 75 such operative stroke.

The two thermostats 35 are similarly adjusted accurately to cause operative action of the switches controlled thereby at substantially the same generator retort 80 temperature.

It is possible to calculate for each installation, approximately the generator retort temperature that will be reached when the gas has been driven from the absorbent and when the expansion or boiling stage in a refrigerating element has been nearly concluded. The two thermostats or their switches are then adjusted to cause a valve throwing stroke of the motor 27 when such 90 generator-absorber temperature is reached or indicated.

The same is true of the pressure gauges with which each generator is preferably equipped. For instance, I show each generator-absorber equipped with its own gauge 39 connected thereto to respond to and indicate the pressure therein. There is a certain fixed relation between pressure and temperature within the generators. The pressure and temperature rise and fall together, and if the thermostats are adjusted to cause a switch over of heat and cooling water between the generators when the temperature reaches, say 300° F. in the generator that is expelling gas, the two gauges 39 will be set to cause a valve throwing action of the motor 27 when approximately 150 pounds pressure is reached in such generators.

Each gauge 39 forms an electric switch in its own electric circuit that is connected to the motor 27 or the motor controlling means in the same manner as the thermostat switches and circuits, and these pressure gauge controlled switches and circuits constitute checks on or adjuncts to the thermostat controlled switches and circuits, or in the nature of emergency or safety devices. If for any reason, a thermostat controlled switch and circuit should not operate when the critical temperature in its generator is indicated, the gauge 39 of such generator, set to close its switch at the generator pressure approximately corresponding to such generator temperature, will operate to cause a valve throwing operation of motor 27, or if the gauge switch does not so operate, the thermostat switch will.

The pressure indicating movable finger 130

or pointer 39', of each gauge is usually coupled into the circuit controlled by that gauge to form the movable switch contact, while a switch contact 39" can be arranged in the 5 gauge to form the normally fixed switch contact. The contact 39" is preferably adjustable around the dial of the gauge so that it can be set at the pressure (say 150) at which it is desired to cause the motor 27 10 to operate, when the pointer 39' will electrically engage contact 39" and close the motor controlling circuit.

For instance, if it is found that it takes 15 six hours to expand the gas from either expansion coil or element A', B', heating elements 30, 31, are employed of sufficient capacity to take approximately the same length of time to expel or exhaust the gas from either generator-absorber and reach 20 the temperature or critical point therein, at which the motor 27 is caused to perform a valve throwing action to shift the heat and cooling water between the generator-absorbers. The length of time between shifts can 25 be increased or decreased by reducing or increasing the heating capacity of the heaters, by increasing the number of B. t. u. applied to the generator-absorbers during generation.

30 In other words, the application of heat and the shift over periods should be so arranged and calculated that when the frost on the outer surface of an expansion coil or element A', B', under refrigeration, 35 begins to melt showing that all of the expanded gas therefrom has been absorbed back in its generator-absorber, the shift over should have taken place at such time, that the other generator-absorber should be 40 cooled to condition to begin absorbing gas expanded from its expansion coil or refrigerating element.

And in this connection, it is again emphasized, that the check valves 8, 8', are constructed and arranged to automatically control the back flow of expanded gas to prolong the refrigerating operation to the maximum and permit more or less slow regular back flow of gas at a rate that does 45 not exceed the capacity of the absorber to take up the gas, maintaining an approximately uniform difference in pressure at opposite sides of said valves 8, 8'.

50 By so constructing and arranging my apparatus, as to greatly prolong the period of gas expansion and refrigeration, and require approximately the same length of time in which to expel the gas from the generators, a long generation period is provided for that requires a minimum heat supply, and hence forcing of the heat supply and overheating and excessive pressures is avoided.

55 I provide the generator-absorbers with pockets 40 extending thereinto and closed

from the interiors thereof and open at their outer ends to removably receive the thermostats 35 and protect the same from the deleterious action of the materials within the retorts. These pockets can be formed by 70 closed end tubes of steel or other suitable material welded in the retort walls, as described in connection with the pocket 33. By thus providing pockets 40 to receive the thermostats, I can remove and replace thermostats and can use standard or other thermostats of commerce, the nature and materials of which prevent use thereof where exposed to the gases and substances within 75 the retorts. 80

I gain advantages for ordinary refrigerator purposes, by the provision of the two U-shaped combined receiver and expansion chamber enlarged hollow bodies A', B', which can be conveniently secured together one over the other, and located in the ice compartment of an ordinary refrigerator R with the pipes 5, 5', extending through the back wall of such refrigerator to the condensers which can be arranged at the exterior of the refrigerator and secured to the back thereof. 90

The generator-absorbers can be located at the exterior of one end of the refrigerator. When the hollow bodies A', B', are thus arranged and secured with the legs of the U-shapes projecting forwardly, plates 45 can be secured at the under sides of the bodies to support water freezing trays 46 that can removably rest between the legs of the U-shapes and can be moved in and out on the tray supporting ledges formed by plates 45, when the door of the refrigerator ice compartment is open. 95

100 However, I do not wish to so limit all features of my invention, as the hollow bodies A', B', might be immersed in brine, or for large refrigeration installations might assume different shapes and forms, such as closely adjacent pipes or coils. 110

115 Also, I do not wish to limit all features of my invention, to use with two individually separate or complete generator-absorber and expansion chamber units, nor to use with one way as distinguished from return circuit systems.

120 By providing two refrigerating units (each comprising its own generator-absorber, condenser, and combined receiver and refrigerating element) that are separate and distinct so far as their refrigerating circuits are concerned, yet which are combined so far as relative operations and exterior refrigerating influences are concerned, I gain certain refrigerating efficiency and advantages and avoid certain refrigerating losses. I find that after each shift over of heat and cooling water between the two generator-absorbers, a length of time elapses before the generator to which the heat has just been 125 130

applied ceases to absorb, and before the generator from which the heat has just been cut off begins to absorb. During this interval, refrigerating expansion can continue in 5 one refrigerating element while the pressure is dropping in the generator-absorber of the other refrigerating element to the point necessary to start boiling or expansion in said last named element. In other 10 words the generating and gas expanding operations overlap at each shift and the provision of separate yet adjacent expansion or refrigerating elements of separate units prevents intervals when no expansion 15 or refrigeration takes place, and utilizes the refrigerating action of one element to chill the other element and refrigerated zone during such overlap.

The motor 27 can be driven by weights, 20 electricity or other power, the application of which is controlled by the thermostat or gauge controlled circuits.

If so desired, the motor 27 can consist of the thermostat controlled electric or weight 25 motors of commerce. For instance, an electric motor that always rotates in the same direction but actuates a pulley or gear 28^a through automatic reversing mechanism. Whenever started the motor rotates the gear 30 or pulley a certain number of revolutions and then comes to rest. The pulley or gear is rotated first in one direction, on one stroke, and on the next stroke in the opposite direction. This is well adapted for raising and 35 then lowering the valve 24. The valve can be weighted to drop or can be spring pulled downwardly. A type of such a thermostat controlled motor is shown, for instance, by Patents Nos. 952991 and 953006, March 22, 40 1910. My invention, however, is not limited to any particular motor type or structure.

In Figs. 11, 12, I show a convenient form of ice mold or tray that can be employed to slide into and from the spaces between the 45 legs of the U-shaped refrigerating elements A', B'. The several refrigerating elements can be suitably assembled and held together for insertion into a refrigerator R, as a unitary structure and to provide for support of 50 and convenient access to and application and removal of the ice molds 46.

For instance, the two horizontal elements A', B', can be firmly supported in parallelism, one over the other, by a supporting and 55 clamping frame work embodying horizontal plates resting against the top and bottom faces of the elements and held thereto by transverse clamping and element supporting bars 47 and vertical clamping bolts 48 co-60 operating with said bars 47.

If so desired, vertically swingable front doors 50 can be provided at the front ends 65 of the refrigerating elements A', B', to close the freezing chambers provided therein by the top and bottom plates 45. These freez-

ing chambers are provided for the ice molds or trays and said chambers are rendered accessible from the front by elevating said doors, the purpose of which is obvious.

It is evident that various changes, modifications and variations might be resorted to, that features might be added or parts omitted, all without departing from the spirit and scope of my invention, and hence I do not wish to limit myself to the exact disclosures hereof.

What I claim is:—

1. Refrigerating apparatus of the absorption type comprising a generator-absorber and a pressure pipe line leading therefrom, 80 in combination with light-pressure lifted check valve means in said line, and relatively heavy pressure-lifted check valve means in said line beyond said first mentioned means in the direction of gas flow. 85

2. Refrigerating apparatus of the absorption type, comprising a generator - absorber, a pressure gas offtake pipe therefrom, a suction intake pipe thereto, means to automatically regulate and control the outflow of gas 90 through said offtake consisting of light-pressure lifted check valve means and relatively - heavy - pressure lifted check valve means arranged beyond said light - pressure lifted check valve means, and means to automatically regulate and control the gas flow 95 into the generator-absorber through said intake consisting of light-pressure lifted check valve means and relatively heavy-pressure lifted check valve means arranged in succession with respect to said light-pressure lifted check valve means and between the same and the generator-absorber. 100

3. Refrigerating apparatus of the absorption type having automatic gas flow controlling check valve means in its gas line embodying a gas passage and a pressure-lifted check valve for said passage, a relatively large capacity gas passage from said first mentioned passage and a relatively-large 110 pressure-lifted check valve for said large capacity passage.

4. An automatic refrigerating apparatus of the absorption type, comprising a pair of 115 separate refrigerating units, each unit consisting of a generator absorber and its heating and cooling means, a condenser, a refrigerating unit, and a connecting pipe line, means being provided for automatically shifting the application of heat and cooling 120 medium from one generator-absorber to the other, the two refrigerating elements being similar in form and capacity and arranged closely together one over the other, each refrigerating element being approximately U-shaped and horizontally arranged, with the U-shapes open at the front and providing 125 supports for removable ice trays adapted to be located between the legs of the U-shape. 130

5. A refrigerating apparatus of the absorption type, comprising a pair of separate refrigerating units, each unit consisting of a generator absorber and its heating and cooling means, a condenser, an individually complete hollow refrigerating body providing a central open refrigerating space, and a connecting pipe line, means being provided for shifting the application of heat and cooling medium from one generator-absorber to the other, the two similar refrigerating bodies secured together in approximate parallelism with their central spaces accessible to receive freezing trays.
- 10 6. Refrigerating apparatus of the absorption type, comprising a pair of separate refrigerating units, each unit consisting of its own generator-absorber, condenser, refrigerating element and connecting combined offtake and suction gas pipe line, the two refrigerating elements being arranged each within the zone cooled by the other, each generator absorber having means for alternately heating and cooling the same, means for periodically cutting off the heat from one generator-absorber and applying cooling means thereto and simultaneously applying heating means to the other generator absorber and cutting off the cooling medium therefrom, and a continuous cooling water coil, the condensers of said units being both arranged in cooled relation to said continuous coil during both generation and absorption.
- 15 7. Refrigerating apparatus of the absorption type, comprising a pair of separate refrigerating units, each unit consisting of its own generator-absorber, condenser, refrigerating element, and connecting combined offtake and suction gas pipe line terminating at the generator-absorber in a return gas suction branch and a valved gas offtake branch, the two refrigerating elements being arranged each within the zone cooled by the other, each generator absorber having means for alternately heating and cooling the same, means for periodically cutting off the heat from one generator absorber and applying continuously flowing cooling means thereto and simultaneously applying heating means to the other generator absorber and cutting off the cooling medium therefrom.
- 20 8. Refrigerating apparatus of the absorption type, comprising separate refrigerating units, each unit embodying its own generator-absorber, condenser, refrigerating element, and connecting gas line, each gas line embodying a check-valve controlled gas offtake from its generator-absorber and a branch pipe forming the absorption gas return discharging into the liquid in the generator absorber, the refrigerating element of each unit arranged in the zone cooled by the element of the other unit, means for alternately heating and cooling the generator-absorbers, means for shifting the heat from one to the other of said generator-absorbers and for simultaneously and oppositely shifting the cooling medium, and means for continuously applying cooling medium to the condensers of both units.
- 25 9. Refrigerating apparatus of the absorption type embodying a generator absorber, a condenser, a refrigerating element, and a connecting gaseous refrigerant pipe line having automatic gas flow controlling check valve means embodying a succession of separate check valves having pressure receiving surfaces of different areas and an intervening gas chamber.
- 30 10. Refrigerating apparatus of the absorption type, comprising a generator-absorber, and a pressure pipe line leading therefrom and arranged, in part at least, to drain back into the generator-absorber, said line including means to prevent back pressure flow and to dehydrate the gas by the provision of an expansion and condensing chamber draining back into the generator-absorber, said means embodying pressure-lifted check valve means admitting gas to said chamber and relatively heavy pressure-lifted check valve means controlling the on flow of gas from said chamber.
- 35 11. Refrigerating apparatus of the absorption type, comprising a generator-absorber, a passage for leading off the gas expelled during generation, a passage for leading in the expanded gas during absorption, and means for automatically controlling the flow of expanded gas into the generator-absorber during absorption consisting of a succession of pressure lifted valve means of progressively increasing capacities and an intervening gas accumulating chamber.
- 40 12. Refrigerating apparatus of the absorption type, comprising a generator-absorber, means for leading off the gas generated in said generator-absorber, means for discharging the expanded gas into said generator-absorber for re-absorption, means for controlling the expanded gas flow into said generator absorber, and means for automatically regulating and controlling the gas flow from said generator and embodying a succession of pressure lifted valve means and an intervening gas expansion and vapor condensation chamber.
- 45 13. Refrigerating apparatus of the absorption type, comprising a generator-absorber, a condenser, a combined receiver and expansion chamber included in a pipe line for flow of gas under pressure from the generator-absorber through the condenser to the chamber without the provision of an expansion valve and a separate receiver, light-pressure lifted valve means arranged in said pipe line between the generator-absorber and the condenser to prevent back

pressure flow toward the generator-absorber, and relatively-heavy pressure-lifted valve means in said line beyond said first mentioned means to provide an intervening gas chamber.

14. A refrigerating machine of the absorption type, embodying a refrigerant line including a generator-absorber, a condenser, and a combined receiver and expansion refrigerating element, said line on the pressure side including a combined expansion valve and dehydrator arranged to drain back into the generator-absorber, and composed of successive ports of different capacity and separate cooperating valves therefor.

15. Refrigerating apparatus of the absorption type comprising a generator-absorber, means being provided for successively heating and then cooling the same, and a refrigerating element operatively connected with said generator absorber to receive the refrigerant therefrom and to permit suction return of expanded refrigerant thereto, said element embodying a hollow approximately U-shaped body, cover plates fitting the opposite sides of said body to provide a refrigerating chamber in the space between the legs of the U-shape, and a front cover for said chamber.

16. Refrigerating apparatus of the absorption type comprising a pair of refrigerating units each embodying a generator-absorber and a refrigerating element consisting of a hollow body providing a central refrigerating chamber having a front end entrance opening, each refrigerating element being operatively coupled to its generator-absorber to receive refrigerant therefrom and to return the expanded refrigerant thereto, the refrigerating elements of the pair of units being arranged adjacent to each other in approximate parallelism.

17. In refrigerating apparatus, in combination, twin generator-absorbers, means for alternately heating said generator-absorbers, each generator-absorber having its own cooling liquid passage, a valve casing providing separate cooling liquid inlets to said passages of the generator-absorbers, respectively, and also providing liquid outlets from said cooling passages, respectively, a slide valve in said casing providing a cooling water common supply duct open to a source of cooling water and having outlet ducts to said inlets, respectively, and also having a common liquid offtake duct with ports to said outlets, respectively, said ports and inlets and outlets being so arranged that when said valve is in one position cooling water will be supplied to one generator-ab-

sorber from said supply duct and the outlet from said generator-absorber will be closed while the inlet to the other generator-absorber will be closed and its outlet open to said common offtake duct, and whereby when said valve is in its opposite position cooling liquid will be cut off from said one generator-absorber and its outlet opened while cooling liquid will be supplied to the other generator-absorber and its outlet closed, and an independent motor for operating said slide valve.

18. In refrigerating apparatus, in combination, twin generator-absorbers, a source of cooling liquid for said generator-absorbers, heaters for said generator-absorbers, an elongated reciprocating unit movable in one direction to one position and in the opposite direction to another position, means whereby said unit when in one position cuts off the supply of cooling liquid to one generator absorber and causes application of heat thereto and cuts off the heat from the other generator-absorber and starts the application of cooling liquid thereto, and whereby the movement of said unit to its other position cuts off heat from said one generator-absorber and causes application of cooling liquid thereto and causes application of heat to said other generator-absorber and cuts off the cooling liquid therefrom, a single normally-inactive independent actuating motor for said reciprocating unit, and a switch-controlled starting circuit for said motor.

19. In refrigerating apparatus, in combination, a generator-absorber, a source of cooling liquid therefor, a heater therefor, normally-inactive movable means controlling the flow of cooling liquid to said generator-absorber and the heating medium to said heater and constructed and arranged to move to one position to cut off the operation of said heater and cause the cooling flow of said liquid and to move to another position to start the operation of said heater and cut off the flow of cooling liquid, and a single independent normally-inactive actuating motor for said means embodying a normally inactive rotary member operatively connected with said means and driven by said motor in opposite directions on successive strokes, said motor constructed and arranged whenever started to cause said rotary member to make a definite stroke and then come to rest, and an independent electric starting circuit for said motor including a normally open switch.

Signed at Oswego, Oswego County, New York, this 9th day of February, 1923.

MAXWELL R. KARGE.
